UNITED STATES PATENT OFFICE.

JOSEPH SOBEL, OF BROOKLYN, NEW YORK, ASSIGNOR TO GENUINE BRONZE FIXTURE CO. INC., OF BROOKLYN, NEW YORK, A CORPORATION OF NEW YORK.

DESIGN FOR A DISPLAY STAND.

Application filed March 21, 1928. Serial No. 25,938. Term of patent 7 years.

To all whom it may concern:

Be it known that I, JOSEPH SOBEL, a citizen of the United States, residing at Brooklyn, in the county of Kings and State of New York, have invented a new, original, and ornamental Design for Display Stands, of which the following is a specification, reference being had to the accompanying drawing, forming part thereof.

In the drawing—

I claim:

The ornamental design for a display stand, as shown.

JOSEPH SOBEL.
